Harold Sherway,
his ATTORNEY.

UNITED STATES PATENT OFFICE.

MICHAEL J. HORKAVE, OF GARY, INDIANA, ASSIGNOR OF ONE-HALF TO STEPHEN BLANER, OF GARY, INDIANA.

SAFETY GAS-VALVE.

1,330,075.

Specification of Letters Patent. Patented Feb. 10, 1920.

Application filed June 7, 1919. Serial No. 302,581.

To all whom it may concern:

Be it known that I, MICHAEL J. HORKAVE, a citizen of the United States, and a resident of Gary, Lake county, and State of Indiana, have invented certain new and useful Improvements in Safety Gas-Valves, of which the following is declared to be a full, clear, and exact description.

This invention relates to safety gas valves and its principal object is to provide means whereby the gas valve stem cannot be manipulated when the knob or handle of the valve is in normal position. Valves of gas stoves are controlled by knobs or handles, and occasionally a gas valve is accidentally opened without the gas being ignited, thus endangering the lives of those present. Small children are attracted by the valves and frequently play with the knobs or handles, and occasionally turn on the gas, with the result that unless discovered in time, asphyxiation of the child and others present may occur. With the present invention the danger of turning the gas on or off without first setting the knob or handle in operative position, is eliminated. The invention consists in a knob or handle for gas valves, having an inoperative position, held in such position by spring pressure, but capable of being moved to operative position. The invention further consists in the several novel features hereinafter fully described and claimed.

The invention is clearly illustrated in the accompanying drawing, in which:

Figure 1 is a cross section through a gas pipe of a kitchen gas stove showing the gas valve in side elevation, and showing in central, vertical section, a simple embodiment of the present invention applied thereto;

Fig. 2 is a side elevation of a fragment of the gas valve, with the device shown in central, vertical section, but in operative position;

Fig. 3 is a detail horizontal section of the knob, taken on the line 3—3 of Fig. 2;

Fig. 4 is a view, partly in end elevation and partly in vertical cross section, the line of section being indicated at 4—4 in Fig. 1;

Fig. 5 is a detail cross section of the knob taken on the line 5—5 of Fig. 1; and

Fig. 6 is a perspective view of a certain clutch member or star wheel used in the device.

Referring to said drawings, the reference character A designates a gas pipe of a kitchen gas stove, B designates one of the gas valves thereof that control the flow of gas from said pipe to a burner (not shown) of the stove, and C designates the valve stem of the valve. As is well known, a knob or handle (not shown) usually is secured upon the valve stem, whereby it may be rotated to turn the supply of gas on or off. The valve stem is usually screw threaded as at c, for the reception of the knob or handle. The safety device, lettered D, comprises in general, a knob or handle 7, longitudinally and rotatively movable with respect to the valve stem C, and clutching means between the knob and stem for clutching it to the valve stem. The knob 7, has a cylindrical recess 8, at its inner end, the face of which is formed with one or more lugs 9, two being shown, which are adapted for engagement with a clutch member or star wheel 10, fixedly secured to the valve stem C. Normally said lugs and star wheel are disconnected from each other, whereby the knob may be rotated without rotating the valve stem. Said lugs 9 are shown as of V-shape formation, adapted to enter the spaces between the arms or points 11 of the star wheel. Co-axially with said recess 8, is a smaller cylindrical recess 12 in which is confined a coiled compression spring 13 which bears against the star wheel 10, and against the bottom or shoulder 14 at the end of the recess 12, and acts to yieldingly hold the knob in inoperative position with the lugs 9 out of contact with the star wheel. The recess 12 has a reduced portion 15 extending to the outer end of the knob, in which fits a tubular valve stem extension 16 that is internally screw threaded as at 18, and fastened upon the valve stem C. The inner end of the tubular valve stem extension 16 bears against the star wheel 10, and locks it on the valve stem C, and its outer end is formed with a head 17 which forms a stop limiting the outward movement of the knob. The star wheel is threaded upon the valve stem and locked in place thereon and rotates therewith and the valve stem extension 16 is locked upon the valve stem against relative rotation. The knob is freely rotatable and longitudinally movable upon the valve stem extension and normally held in contact with the head 17.

of the valve stem extension 16, by the spring 13.

With the parts in position illustrated in Fig. 1 the knob may be rotated indefinitely without affecting the valve stem, and consequently, the valve cannot be opened or closed. To turn the valve stem in either direction the knob is first moved toward the valve, upon the valve stem extension 16, against the spring, and manipulated to bring the lugs 9 into register with the spaces between the arms 11 of the star wheel 10, and thereupon moved toward the valve to bring the lugs into the spaces between the arms 11, in which position the valve stem C may be turned by turning the knob or handle. Upon releasing the knob the spring returns it to inoperative position, with the lugs 9 disconnected from the star wheel, in which position it may be turned freely without affecting the valve stem.

From the foregoing description it is apparent that the valve cannot be manipulated while the knob is held in inoperative position and that the danger, present with the fixed knob or handle, is reduced to a minimum, and that the knob may be instantly clutched to the valve stem and made operative.

More or less variation of the exact details of construction is possible without departing from the spirit of this invention; I desire, therefore, not to limit myself to the exact form of the construction shown and described, but intend, in the following claims to point out all of the invention disclosed herein.

I claim as new, and desire to secure by Letters Patent:

1. A safety gas valve, comprising a gas valve stem, having a threaded end portion, a star wheel fixedly secured on said threaded end portion of the valve stem, an internally threaded tubular valve stem extension secured on said threaded end portion of the valve stem, a knob having an operative and an inoperative position, rotatively and longitudinally movable on said valve stem

extension, and formed with a lug adapted, when in operative position, to operatively engage said star wheel, and a coiled compression spring for yieldingly holding said knob in inoperative position with said lug out of engagement with said star wheel.

2. A safety gas valve, comprising a gas valve stem, having a threaded end portion, a star wheel fixedly secured on said threaded end portion of the valve stem, an internally threaded tubular valve stem extension secured on said threaded end portion of the valve stem, a knob having an operative and an inoperative position, rotatively and longitudinally movable on said valve stem extension and formed with a cylindrical recess at one end in which the star wheel is contained in both positions of the knob, and a coaxially reduced recess beyond the same, the face of the first mentioned recess having a lug adapted, when in operative position, to operatively engage said star wheel, and a coiled compression spring in said reduced recess bearing against said star wheel and bottom of the recess, for yieldingly holding said knob in inoperative position with said lug out of engagement with said star wheel.

3. A safety gas valve, comprising a gas valve stem, a star wheel fixedly secured thereon, a tubular valve stem extension fixedly secured on said stem, a knob rotatably mounted and lengthwise movable on said stem extension from an inoperative position to an operative position and having a recess, the face of which is formed with a lug capable of being operatively engaged with said star wheel, when in operative position, said star wheel being contained in said recess in both positions of the knob, and a coiled compression spring confined in a recess formed in said knob, bearing against said star wheel and bottom of the recess in which it is confined, said spring operating to yieldingly hold said knob in inoperative position with the lug out of engagement with said star wheel.

MICHAEL J. HORKAVE.
